UNITED STATES PATENT OFFICE.

JOHN ROMMEL, OF NIAGARA FALLS, NEW YORK.

NECKTIE-FASTENER.

SPECIFICATION forming part of Letters Patent No. 628,118, dated July 4, 1899.

Application filed September 14, 1898. Serial No. 690,927. (No model.)

To all whom it may concern:

Be it known that I, JOHN ROMMEL, a citizen of the United States, residing at Niagara Falls, in the county of Niagara and State of New York, have invented certain new and useful Improvements in Necktie-Fasteners; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 The special object of the invention is to make a necktie-clasp of sheet metal so constructed that it may be readily applied and will not be liable to get out of position. This has the effect of always preserving the proper 20 local relation of the necktie to the collar so as always to present a neat and attractive appearance.

Figure 1 of the drawings is a plan view of the necktie-fastener before it has been applied, and Fig. 2 an elevation showing its true 25 position on the necktie.

In the drawings, A represents my sheet-metal fastener, cut, preferably, on a circle of about fifty inches in diameter. Through the 30 middle runs the longitudinal slots a a', between which extends the longitudinal spring a². The latter is over the half-circle notches a³ in the bottom of the slot a'. The neck of collar-button fits in these notches and is retained there by the spring a². At the right 35 end of the slot a' is a circular hole a⁴, large enough for a collar - button head to pass

through. At the bottom and on each side is a projection a⁵, with rounded ends, which are to be bent around the bottom of the collar, 40 while on each end is a pointed projection a⁶ for securing the metallic sheet to the cravat or necktie. In each corner and in the middle are made small holes by which the fastener may be conveniently sewed to the cravat to hold them together in the event of the 45 breaking of any of the points or projections.

The fastener is first secured on the inside of the cravat with the circular hole a⁴ toward the free end thereof, so that it will occupy 50 the space commencing seven inches from the center of the necktie and ending at the tenth inch from said center.

In putting the fastener on the necktie the two hooks a⁵ a⁶ work under the collar, while 55 the head of collar-button is passed through the hole a⁴. The band is then pulled to the right until the necktie is in the exact position desired.

What I claim as new is—

A sheet - metal necktie - fastener having the longitudinal slots a a', the intermediate spring a², the notches a³, the hole a⁴ for collar-button head, the hooks a⁵ to catch under the collar, and the projection a⁶ for holding 65 the fastener to cravat, all constructed and arranged as shown and described.

In testimony whereof I affix my signature in presence of two witnesses.

JOHN ROMMEL.

Witnesses:
